(Cl. D72—1)

To all whom it may concern:

Be it known that we, Henning A. Eklind, a citizen of the United States, and Otto J. Blomberg, a subject of the King of Sweden, residing at Chicago, Cook County, Illinois, have invented a new, original, and ornamental Design for a Brake Signal Light, of which the following is a specification, reference being had to the accompanying drawing, forming a part thereof.

Fig. 1 is a detail perspective view of a brake signal light showing our new design;

Fig. 2 is a bottom plan view thereof;
Fig. 3 is a front elevation thereof; and
Fig. 4 is a rear elevation thereof.

We claim:

The ornamental design for a brake signal light, as shown.

HENNING A. EKLIND.
OTTO J. BLOMBERG.
